C. E. CASE.
STEAM GENERATOR.

No. 63,469.

Patented Apr. 2, 1867

United States Patent Office.

CHARLES E. CASE, OF XENIA, OHIO.

Letters Patent No. 63,469, dated April 2, 1867.

IMPROVEMENT IN STEAM GENERATORS.

The Schedule referred to in these Letters Patent and making part of the same.

TO ALL WHOM IT MAY CONCERN:

Be it known that I, CHARLES E. CASE, of Xenia, in the county of Green, and State of Ohio, have invented certain new and useful improvements in Steam Generators or Boilers; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in a novel manner of constructing a steam boiler or generator, to prevent the same from being injured by the fire. It further consists in arranging within the generator thus constructed a coiled pipe with a spray nozzle, for heating and delivering the water into the generator, to be instantly converted into steam.

The drawing represents a vertical section of the generator and its furnace, as it is intended for use.

A represents the boiler or vessel, the body, *c*, of which is constructed of iron or steel in the usual manner, and preferably in the form about as represented. To this iron body I then apply a covering composed of fire-brick, clay, and asbestos mixed together, as represented by *b* of the drawing; the asbestos being incorporated with the clay, while the latter is in a plastic condition, the same as hair is mixed into mortar. This material forms a coating, as nearly indestructible by fire as is possible to obtain, in a suitable condition to be applied as a coating to the iron. To hold this coating in place, and prevent it from being broken or injured, I cover it with a thin outer casing of copper, as represented by *a*. The coating of asbestos and clay will be made thickest on those parts most directly exposed to the action of the fire, which in this instance is at the bottom, while at the sides the coating is thinner, and at the top it is omitted entirely, as the upper portion of the vessel is intended to operate as a superheater of the steam; and because also the intensity of the heat at this point is not intended to be such as to render the protection necessary. In other forms of the generator the coating may be applied to the entire surface of the vessel, this of course depending upon its form and location with reference to the fire or furnace. The vessel thus constructed is suspended, by a series of arms, *d*, within a furnace as represented. The water is injected by means of a force-pump through the pipe *F* into the coil *B*, where it is rapidly heated and ejected through the finely perforated nozzle *C*, when it is at once converted into steam, which rises to the upper portion of the vessel, where it is superheated and escapes thence through pipe *E* to the cylinder of the engine. In order to start the generator, the water may be admitted through a separate pipe leading from a reservoir situated above the level of the vessel *A*, said pipe being provided with suitable cocks or valves, to regulate its admission as desired; or if the pump be connected with a reservoir of sufficient elevation, it may be admitted through the same pipe, as the valves in the pump all open toward the vessel, and will therefore permit the water to flow from the reservoir through the pump and pipe *F* into the generator, on opening a cock or valve suitably located between the reservoir and the generator. It will be understood that in this, as in all similar generators, the water is to be injected at intervals in limited quantities, sufficient to generate enough steam to operate the piston once, a new supply being furnished at each stroke of the piston.

Having thus described my invention, what I claim is:

1. The application to the exterior of steam generators of a coating composed of asbestos mixed with fire-clay, and held in place by a metal covering, as herein shown and described.
2. In combination with the generator, constructed as herein described, I claim the coiled pipe *B*, terminating in the perforated nozzle *C*, all arranged to operate as set forth.

Witnesses:

W. C. DODGE,
CHAS. HADAWAY.
